(No Model.)

H. P. CAYCE.

SASH BALANCE.

No. 439,742.

Patented Nov. 4, 1890.

UNITED STATES PATENT OFFICE.

HENRY P. CAYCE, OF SAN MARCOS, TEXAS.

SASH-BALANCE.

SPECIFICATION forming part of Letters Patent No. 439,742, dated November 4, 1890.

Application filed August 9, 1890. Serial No. 361,508. (No model.)

To all whom it may concern:

Be it known that I, HENRY P. CAYCE, a citizen of the United States, residing at San Marcos, in the county of Hays and State of Texas, 5 have invented certain new and useful Improvements in Sash-Balances; and I do declare the following to be a full, clear, and exact description of the invention, such as will enable others skilled in the art to which it 10 appertains to make and use the same, reference being had to the accompanying drawings, and to the letters of reference marked thereon, which form a part of this specification.

My invention has relation to sash balances 15 and hoisters; and it consists in the novel construction and arrangement of its parts.

In the accompanying drawings, Figure 1 is a face view of a window-frame and sash with my invention attached thereto. Fig. 2 is a 20 longitudinal sectional view of Fig. 1, showing the left-hand side. Fig. 3 is also a longitudinal sectional view of Fig. 1, showing the right-hand side. Fig. 4 is a detail view.

My invention is described as follows: I 25 make my sash A with a groove a in their upper edge. Near both ends of said grooves are journaled pulleys a' . The construction of the upper and lower sash is identical. In 30 the top of the frame and on each side of the window are journaled pulleys a^2 and a^3 , respectively. One end of a rope C is securely fixed to the top of the frame at point c; then 35 it runs under the pulleys a' in the groove a of the upper sash, then up and over the pulley a^3 ; then it descends to the lower sash and runs under the pulleys a' in the groove a of said lower sash; then it ascends and passes over the pulley a^2 , from which it runs down to a cleat B. Said cleat consists of a right 40 and left wing, with a V-shaped groove b between the two. One end of each of these wings tapers in a straight line upward and outward to a point, and said points indicate opposite directions. Said cleat is also provided with perforations b' , through which 45 pass screws which attach said cleat to the window-frame.

My invention is operated as follows: When the sash are in the position as shown in Fig.

1, and it is desired to raise the lower one, this 50 can be done by simply pulling cord C, and when the sash is raised to the desired height the cord is brought down under the lower point of the cleat B, then up in the groove b , and under the upper point of said cleat. This 55 will hold the sash in position. When the sash are in the position as shown in Fig. 1, and it is desired to lower the upper one, this can be done by unwinding cord C from the cleat and letting it run over the pulley a^2 . 60 The weight of the upper sash will cause it to descend, and when it is down a sufficient distance the cord can be wound around the cleat. Thus the said upper sash will be held in the 65 desired position. When the sash are in the 70 position last above described and it is desired to raise the upper one, place one hand on the lower sash and pull the cord with the other. When the sash is closed, the cord is wound around the cleat. When the sash are 75 in the position as shown in Fig. 1, and it is desired to raise the lower one and lower the upper one at the same time, all that is necessary to be done is to push the lower sash up, and the upper sash will of its own weight descend, and thus we have the weight of one 80 sash balancing the weight of another.

Having described my invention, what I claim as new, and desire to secure by Letters Patent, is—

The combination of a window-frame provided with the pulleys a^2 and a^3 , sash A, provided with the grooves a , and pulleys a' , working in said grooves, and cord C, having one end attached to the upper part of the frame at c, 85 passing thence under pulleys a' in the upper sash, thence over pulley a^3 , thence down and under pulleys a' in the lower sash, thence up and over pulley a^2 , thence down to a cleat B, all substantially as shown and described, and 90 for the purposes set forth.

In testimony whereof I affix my signature in presence of two witnesses.

HENRY P. CAYCE.

Witnesses:

THOMAS TAYLOR,
WILLIAM W. HARDY.
